UNITED STATES PATENT OFFICE.

WILLIAM MORGAN, OF HAVRE, MONTANA.

ADJUSTABLE HAME AND TRACE CONNECTION.

1,198,864.

Specification of Letters Patent. Patented Sept. 19, 1916.

Application filed April 10, 1916. Serial No. 90,119.

To all whom it may concern:

Be it known that I, WILLIAM MORGAN, a citizen of the Dominion of Canada, and a resident of Havre, in the county of Hill 5 and State of Montana, have invented a certain new and useful Improvement in Adjustable Hame and Trace Connections, of which the following is a specification.

My present invention relates generally to 10 hame and trace connections, and more particularly to an adjustable hame and trace connection of that type known as bolt connector, in which the trace attaching member is pivotally mounted upon a bolt extending 15 longitudinally of, and connected to, the hame in spaced relation thereto.

The object of my invention is to provide 20 for simple instantaneous adjustment of the trace attaching member with respect to the hame bolt, and its movable support in selected adjustment to regulate the point of draft and thus obviate angular strains upon the hame likely to cause sore necks and sore shoulders in its use.

25 In the accompanying drawing illustrating the preferred form of my invention—Figure 1 is a perspective view of a hame provided with my improvements. Fig. 2 is a side view of a portion thereof. Fig. 3 is a cross section taken substantially on line 3—3 of Fig. 1, with the trace connector in operative position. Fig. 4 is a view similar to Fig. 3 illustrating the trace attaching member turned to position permitting of its vertical adjustment upon the hame bolt.

Referring now to these figures, I have shown in Fig. 1 a hame bolt 10 rigidly secured in spaced substantially parallel relation to the outer edge of the hame 11 by 40 means of attaching eyes 12 rigid with the hame, the trace attaching member, which with the bolt 10 forms the hame and trace connection, consisting of the usual bolt 13 with its sleeves 14, which pass through the 45 tug loop, and having upper and lower arms 15 through the outer ends of which the bolt 13 passes, the inner ends of these arms 15 being loosely pivotally disposed upon the hame bolt 10 and being, in accordance with 50 my invention, provided at one side with laterally projecting ribs 16 as best seen in Figs. 3 and 4. Also, in accordance with my invention, I provide the outer edge of the hame 11 with a locking plate 17 secured in 55 the space between the same and the bolt 10

and extending for substantially the full length of the said bolt, the said locking plate being provided with a plurality of transverse grooves 18 for the reception of the ribs 16 of the arms 15 before mentioned. 60

By reference to Fig. 3 it will be noted that, with the trace attaching member in its operative position, the ribs 16 are in engagement with corresponding grooves 18, and by a comparison of this figure with 65 Fig. 4, it will be noted that, in order to adjust the trace attaching member, it is simply necessary to rotate the same upon the bolt 10 until the ribs 16 are out of the grooves, the trace attaching member being 70 then movable longitudinally of the bolt 10 to selected vertical adjustment, and will be movably held in such adjustment when the trace attaching member is again swung to the operative position as shown in Fig. 3. 75

It is obvious from the foregoing that I provide an adjustable hame and trace connection of what is known as the bolt type, having all of the natural strength and flexibility incident to the usual connection of 80 this type, and having in addition thereto strong, durable, and effective means whereby it may be movably held in selected vertical position to secure the desired line of draft with respect to the hame. 85

I claim:—

A hame and trace connection of the character described, including a hame having a spaced parallel hame bolt and a plurality of eye bolts outstanding from the hame and 90 in which said hame bolt is secured, one of said eye bolts being located centrally of the hame bolt, a trace attaching member including upper and lower spaced arms pivoted at one end upon said hame bolt at opposite 95 sides of said central eye bolt and movable lengthwise of the hame bolt, and a locking plate rigid with the hame adjacent to and parallel with the hame bolt thereof and provided with a plurality of transverse grooves 100 extending the full width thereof, said arms of the trace attaching member having ribs at one side of their pivoted ends to enter said grooves of the locking plate and movably hold the trace attaching member in 105 adjusted position on the hame bolt.

WILLIAM MORGAN.
